DES. 2427

Samuel W. Gibbs of Albany, N.Y.

Letters Patent No. 2427. Dated Aug. 21, 1866.

Design for the Plates of a Stove.

The Schedule referred to in these Letters Patent and making part of the same.

To all whom it may concern:

Be it known that I, Samuel W. Gibbs of the City of Albany in the County of Albany and State of New York, have invented or produced a new and original Design for the plates of a cylinder stove, or Top and Base, the same Top and Bottom being used for a sheet iron cylinder, as well as a cast cylinder, a drawing of which is herewith accompanied.

That I claim as my invention and desire to secure by Letters Patent is, The Design for the plates of a stove as shown and described.

Witnessed,

S. W. Gibbs.

G. C. Fowler.
